UNITED STATES PATENT OFFICE.

SAMUEL TOLLEY, OF ABINGDON, ILLINOIS.

POLE OR TONGUE CAP FOR NECK-YOKE CONNECTIONS.

1,253,909.

Specification of Letters Patent. Patented Jan. 15, 1918.

Application filed August 7, 1917. Serial No. 184,904.

To all whom it may concern:

Be it known that I, SAMUEL TOLLEY, a citizen of the United States, residing at Abingdon, in the county of Knox and State 5 of Illinois, have invented a new and useful Pole or Tongue Cap for Neck-Yoke Connections; and I do hereby declare the following to be a full, clear, and exact description of the invention, such as will enable others skilled in the art to which it 10 appertains to make and use the same.

This invention relates to an improved tongue or pole cap, and one of the objects of the invention is to provide a simple, 15 efficient and practical device of this kind comprising improved features of construction.

A further object of the invention is the provision of a pole cap having improved 20 means for detachably connecting a neck yoke thereto.

A further object of the invention is the provision of a pole cap having a forwardly extending prong or tongue terminating in a 25 hook, and provided with an elongated cavity in its under portion, in which a latch (which is spring tensioned) is pivotally mounted, the spring acting to throw the latch in contact with the hook, thereby retaining the 30 usual loop (not shown) of a neck yoke (not shown) in engagement with said pole cap.

A further object of the invention is the provision of a latch having a spring connection and pivotally mounted in said cavity, 35 whereby said spring may hold the latch open, or in contact with said hook.

A further object of the invention is the provision of means on the body of the latch to be engaged by the loop of the neck yoke 40 (not shown) when said yoke is being moved off the cap, for closing the latch in contact with the hook.

In practical fields the details of construction may necessitate alterations falling within 45 in the scope of what is claimed.

The invention comprises further features and combination of parts as hereinafter set forth shown in the drawings and claimed.

In the drawings:—

50 Figure 1 is a view in elevation of the improved pole cap constructed in accordance with the invention and applied to a pole or tongue.

Fig. 2 is a view partly in section and 55 partly in elevation of the pole cap, the

tongue, and the prong of the cap, showing the latch open.

Fig. 3 is a sectional view on line 3—3 of Fig. 1.

Fig. 4 is a view in side elevation of another form of pole cap as applied to a pole.

Fig. 5 is a view partly in section and partly in elevation of the structure shown in Fig. 4, showing the latch open.

Fig. 6 is a sectional view on line 6—6 of Fig. 4.

Referring more especially to the drawings 1 designates a portion of a wagon pole, which is provided with a reduced extension end 2, to which the pole cap 3 (which is 70 provided with a hollow portion 4) is fitted, there being bolts 5 passing through the end extension and the wall of the hollow part of the cap, to secure the same in place. Formed integrally with the cap and extending downwardly and forwardly is a 75 prong 6, which terminates at its extremity in a hook 7. The under portion of the cap substantially immediately above the hook 7 is provided with a cavity comprising an 80 elongated portion 8, an enlarged portion 9, adjacent to which a recess 10 is constructed. Pivotally mounted upon the pin 11, which is disposed transversely of the cavity adjacent where the elongated portion 85 thereof merges into the enlarged part 9, is a latch 12. The latch 12 is in the form of a bell crank lever, and its longer arm 13 has its extremity curved at 14, to engage the hook 7, as shown in Fig. 1, in order to 90 retain a loop of a neck yoke (not shown) on the pole cap. A contracting tension spring 15 has one end connected at 16 to the shorter arm of the bell crank latch while 95 its other end is connected at 17 to the inner wall of the enlarged portion 9 of said cavity. By the contraction of said spring 15 the free end curved part 14 of the latch normally engages said hook 7, while the extremity of the shorter arm 18 normally engages the recess 10. When the latch is 100 closed as shown in Fig. 1, said shorter arm 18 is so embedded in the under part of the cap as to avoid any obstructions to the loop of the neck yoke when slipping on the cap. When the loop of the neck yoke slips over the cap, it contacts with the longer arm of the latch, and automatically opens, and after the loop passes the longer arm of the latch, 105 the latch consequently returns to its normal 110

position through the action of the spring. In Figs. 5 and 4 the cavity of the pole cap comprises the elongated portion 19 and the enlarged portion 20, and the latch consists of a circular disk 21 pivoted upon the pin 22 (which passes through the opposite walls of the enlarged portion of said cavity) and the arm 23, which projects integrally from the edge of the disk. By means of the pin 22 said disk 21 is mounted in the enlarged part 20 of said cavity. Connected at 24 to the inner wall of the portion 20 of said cavity is one end of a spring 25, its other end is connected at 26 eccentrically to the disk. Said spring is so connected that it may contract on either side of the pivot pin 22, whereby the arm 23 of the latch may be held open into the elongated part 19 of said cavity or closed with its curved end 27 in contact with the hook 7. Projecting radially from the disk 21 is a lug 28, which is designed to be engaged by the finger of the operator, or by the loop of the neck yoke (not shown) when it is slipping off from the cap whereby the disk may be rocked and the arm 23 consequently closed. When the loop of a neck yoke is being slipped over the pole cap shown in Figs. 4 and 5, said loop will contact with the arm 23 and move the same into engagement with the elongated portion 19 with said cavity, after

which an operator may place his finger upon the projection 28 and rock the disk and restore the arm 23 in contact with the hook 7.

The invention having been set forth what is claimed as new and useful is—

A pole cap comprising a body having a downwardly and forwardly extending prong, its forward end terminating in a hook, the under part of the body immediately over the hook having a cavity comprising an enlarged part and an elongated part, a disk member rockably mounted in said enlarged part and having an arm projecting from its edge, a spring having one end connected to the inner wall of the enlarged part of the cavity and having its other end so connected to the disk eccentrically as to hold the arm either in contact with the hook or in engagement with the elongated part of the cavity, said disk having a lug to be engaged by an operator's finger for rocking the disk, whereby the arm may engage the hook or the cavity.

In testimony whereof I have signed my name to this specification in the presence of two subscribing witnesses.

SAMUEL TOLLEY.
